Arnold D'Angelo, New York, N. Y.

Application July 12, 1947, Serial No. 140,247

Term of patent 3½ years

(Cl. D29—23)

To all whom it may concern:

Be it known that I, Arnold D'Angelo, a citizen of the United States of America, residing at New York, in the county of New York and State of New York, have invented a new, original, and ornamental Design for a Wall Plaque, of which the following is a specification, reference being had to the accompanying drawing, forming part thereof.

I claim:

The ornamental design for a wall plaque, as shown.

ARNOLD D'ANGELO.
